R. NORMAN

MINING MACHINE TRUCK

Original Filed May 19. 1922

Patented Feb. 5, 1924.

1,483,053

UNITED STATES PATENT OFFICE.

ROY NORMAN, OF ST. LOUIS, MISSOURI, ASSIGNOR TO SULLIVAN MACHINERY COMPANY, A CORPORATION OF MASSACHUSETTS.

MINING-MACHINE TRUCK.

Application filed May 19, 1922, Serial No. 562,231. Renewed June 18, 1923.

To all whom it may concern:

Be it known that I, ROY NORMAN, a citizen of the United States, residing at St. Louis, in the county of St. Louis and State 5 of Missouri, have invented certain new and useful Improvements in Mining-Machine Trucks, of which the following is a full, clear, and exact specification.

My invention relates to mining machine 10 trucks.

It has for its object to provide an improved truck adapted to transport a mining machine and of an improved construction whereby it is possible to load the mining machine from either end of the truck or to unload the machine from either end of the latter thereby materially facilitating the process of loading or unloading under certain mining conditions. A further object of my invention is to provide an improved truck especially adapted to use with long wall machines having the characteristics above set forth and provided with improved means whereby the mining machine 20 may be connected to the truck during loading or unloading with facility, and held in transport position on the truck.

In the accompanying drawings, I have shown for purposes of illustration one embodiment which my invention may assume 30 in practice.

In these drawings,—

Fig. 1 is a plan view of a truck constructed in accordance with my improvement.

Fig. 2 is a side elevation of the same, the machine being shown in a loaded position in dotted lines.

Fig. 3 is a diagrammatic view showing a mining machine unloading from either 40 end of the truck.

In my improved construction the truck body 1 is preferably provided with usual guide surfaces 2 at its sides and is also preferably but not necessarily mounted upon 45 wheels 3 at points on either side of its transverse center line, while each end of the truck is open and adapted to receive a mining machine.

The truck body of my improved construction 50 is herein made of uniform transverse section above its wheels to provide the usual machine carrying portion and provided with flared end portions 4 each also having the usual guiding surfaces forming a con-

tinuation of the guide surfaces 2. To facilitate the movement of the mining machine relative to these ends, a plate 5 is also preferably disposed over the bottom of each of the flared portions as shown and the end of this plate as at 6 is bent slightly 55 downward to form a portion contacting with the bottom end over which the machine may slide freely up onto the body of the plate 5 when the end of the truck is depressed as illustrated in Fig. 3.

In order to permit the flexible feeding member of a mining machine to be connected to the truck without obstructing either machine receiving end, I have also herein cut away as at 7 each portion 6 and 60 provided an abutment 8, herein in the form of a chain fork, in a plate 9 disposed beneath the plate 5. In order to enable the machine to be held in transport position upon the truck, I have also provided up-standing members 10 at either side of the truck adjacent the beginning of each flared portion thereof and have provided transverse openings 11 in these upstanding portions adapted to receive one or more rods 80 or bars 12 which will thus be disposed above the cutter bar of the mining machine and in front of the machine frame in such a manner as to prevent movement of the latter in one direction relative to the truck. 85 Cooperating with this holding means I have provided one or more pins 13 adapted to be received in corresponding openings 14 in the bottom of each flared end and near the extremity thereof, which are adapted to engage with the opposite end of the machine. To prevent loss of these pins, chains 15 herein connect them to the truck. Attention is also directed to the fact that at 90 each side of each end of the truck I have provided a combined feed member hook and mule haulage connection comprising a hook 16 adapted to be engaged by the flexible feeding member on the mining machine to permit the latter to move relative to the truck during unloading and an aperture 17 adapted to permit a mule haulage connection to be made to the truck if desired.

As result of my improved construction 100 it will be noted that all necessity for turning the truck around to receive a mining machine is obviated, the truck being capable of receiving the mining machine at

either end and thereby materially reducing the time and labor required to load and unload the machine at different places. It will also be observed that the construction is such as to permit the machine to be held securely in transport position on the truck while through the provision of the connections for the flexible feeding member, it is possible for the machine to be unloaded or loaded with facility irrespective of which end of the truck is used.

While I have in this application specifically described one embodiment which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine truck comprising a body having provision for receiving a mining machine at either end thereof.
2. A mining machine truck comprising a body having provision for discharging a mining machine at either end thereof.
3. A mining machine truck comprising a body having a flared mining machine receiving portion at each end thereof.
4. A mining machine truck comprising a body having a flared mining machine receiving portion at each end thereof and an intermediate portion of uniform cross-section.
5. The combination with a mining machine truck having provision for receiving a mining machine at each end thereof, of means for holding a machine in position therein without interfering with said function.
6. The combination with a mining machine truck having provision for discharging a mining machine at each end thereof, of means for holding a machine in position therein without interfering with said function.
7. A mining machine truck comprising a truck body having truck wheels substantially midway between its ends and provision for receiving a mining machine at either end thereof.
8. A mining machine truck comprising a truck body having truck wheels substantially midway between its ends and on opposite sides of its transverse center line and provision for receiving a mining machine at either end thereof.
9. A mining machine truck comprising a body portion adapted to receive a mining machine at either end thereof and adapted to pivot about different longitudinally spaced pivots when a load is moved longitudinally over different ends of said portion.

10. A mining machine truck comprising a wheeled body portion adapted to receive a mining machine at either end thereof and adapted to pivot about different sets of wheels when a load is moved longitudinally over different ends of said portion.

11. The combination with a mining machine truck comprising a truck body having truck wheels substantially midway between its ends and provision for receiving a mining machine at either end thereof, of flexible feed member abutments for loading or unloading at either end.

12. The combination with a mining machine truck comprising a truck body having truck wheels substantially midway between its ends and provision for receiving a mining machine at either end thereof, of flexible feed member abutments at either end thereof disposed out of the path of a mining machine.

13. The combination with a mining machine truck comprising a truck body having truck wheels substantially midway between its ends and provision for receiving a mining machine at either end thereof, of loading and unloading flexible feed member abutments at each end thereof, the loading abutments being disposed substantially in the center line of the truck body out of the path of a mining machine.

14. A mining machine truck comprising a truck body having truck wheels substantially midway between its ends and provision for receiving a mining machine at either end thereof including at each end an inclined bottom contacting portion over which a machine is adapted to slide.

15. A mining machine truck comprising a truck body having truck wheels substantially midway between its ends and provision for receiving a mining machine at either end thereof including an inclined bottom contacting means at each end comprising a plurality of laterally spaced depending portions and a flexible feed member abutment accessible between said portions.

16. The combination with a mining machine truck having an open end to permit the passage of a mining machine through the same, of machine holding means including a removable means disposed across said truck and engageable by a machine thereon.

17. In a mining apparatus, a mining machine truck, a mining machine thereon having a frame and a longitudinally extending cutter bar, and means for retaining said machine on said truck, including means disposed transversely of said truck over said bar and engageable with said machine frame.

18. The combination with a mining machine truck having an end open to permit the passage of a mining machine through the same, of machine holding means includ-

ing a removable cross-bar at one end of said truck and a removable pin at the other end thereof.

19. The combination with a mining machine truck having opposite ends open to permit the passage of a mining machine through the same, of machine holding means operative to permit the passage of a machine when desired.

10 20. The combination with a mining machine truck having opposite ends open to permit the passage of a mining machine through the same, of machine holding means operative to permit the passage of a machine 15 when desired and including holding means acting on the opposite ends of the machine.

21. The combination with a mining machine truck having provision for receiving a mining machine at either end thereof, of 20 loading and unloading flexible feed member abutments at opposite ends thereof, and means for holding a machine in position thereon without interfering with said loading and unloading function.

22. The combination with a mining machine truck having open ends adapted to receive a mining machine, of flexible feed

member engaging abutments at opposite ends hereof, and removable means at each end of a machine thereon for holding said 30 machine in position thereon.

23. The combination with a mining machine truck having open ends adapted to receive a mining machine, of flexible feed member engaging abutments including a 35 loading abutment and an unloading abutment at opposite ends thereof, and removable means at each end of a machine thereon for holding said machine in position 40 thereon.

24. The combination with a mining machine truck having open ends adapted to receive a mining machine, of flexible feed member engaging abutments including a 45 loading abutment and an unloading abutment at opposite ends thereof, said loading abutment being disposed below the machine path and the unloading abutment at the side thereof, and removable means at each end of a machine thereon for holding said 50 machine in position thereon.

In testimony whereof I affix my signature.

ROY NORMAN.
